[57] CLAIM

The ornamental design for a hinge-lid cigarette pack, as
shown and described.

DESCRIPTION

FIG. 1 is a side elevational view of a hinge-lid cigarette
pack showing my new design;

FIG. 2 is a front elevational view thereof;

FIG. 3 is a perspective view of the package;

FIG. 4 is a perspective view thereof with the lid in an
opened position;FIG. 5 is a side elevational view of a second embodiment
of the design shown in FIG. 1, with the opposite
side being a mirror image thereof;

FIG. 6 is a front elevational view thereof;

FIG. 7 is a perspective view thereof; and,

FIG. 8 is a perspective view with the lid in an opened
position.The undisclosed top, bottom and rear views are planar
and unornamented.Fig. 2
